Invention

Rimmon & Fay,
by Crosby & Gregory, Atts.

UNITED STATES PATENT OFFICE.

RIMMON C. FAY, OF MILFORD, ASSIGNOR TO GEORGE DRAPER & SONS, OF HOPEDALE, MASSACHUSETTS.

SPINDLE FOR SPINNING-FRAMES.

SPECIFICATION forming part of Letters Patent No. 253,025, dated January 31, 1882.

Application filed July 29, 1881. (No model.)

To all whom it may concern:

Be it known that I, RIMMON C. FAY, of Milford, Worcester county, State of Massachusetts, have invented an Improvement in Spindles for Spinning-Frames, of which the following description, in connection with the accompanying drawings, is a specification.

This invention in spindles is an improvement on the class of sleeve-whirl spindles such as represented in United States Patent No. 227,129, granted to Rabbeth, dated May 4, 1880, to which reference may be had.

My invention has for its object to provide the supporting-tube with a catch so located thereon as to engage a shoulder within the whirl-sleeve and prevent the spindle being lifted during the usual strain of doffing, yet permitting the spindle and sleeve-whirl to be removed from the supporting-tube, when it is desired to do so for any purpose, by deflecting or drawing the spindle and sleeve-whirl in the proper direction. The pintle of the spindle is inserted in a bolster-bearing surrounded by an elastic or yielding packing, so that the spindle and bearing may be tipped or turned backward in the supporting-tube far enough in an opposite direction from which it is tipped when the bobbins are being doffed to cause the edge of the shoulder of the sleeve-whirl to fall in a line outside of the end of the catch extended from the supporting-tube, when the shoulder of the sleeve-whirl may be lifted above the end of the catch. The diameter of the circular space between the shoulder of the whirl-sleeve and the external diameter of the supporting-tube and the length of the catch radially from the said tube are such that the shoulder strikes the support just after the sleeve-whirl is moved far enough for the shoulder thereon (the sleeve-whirl being lifted) to pass the said catch, thus avoiding such accidental strain on the spindle as would deflect it or put a permanent bend in the same.

Figure 1 represents in elevation and vertical section a sufficient portion of a sleeve-whirl spindle, its supporting-tube, and parts located thereon to illustrate my invention; and Fig. 2 is a cross-section thereof on the dotted line $\alpha\alpha$ of Fig. 1.

The spindle a , its attached sleeve-whirl b , supporting-tube c , bolster d , and elastic pack-

ing e , and foot-step f are all as usual in spinning-frames.

I have provided the lower end of the sleeve-whirl with an inwardly-extended shoulder, 2, 55 and the support e with a catch, 3, which, when the spindle a stands in vertical position, extends over the vertical inner edge of the shoulder 2, as shown in Fig. 1. This catch 3 will be located at the front side of the tube e , so that as the spindle is moved or tipped a little in the direction of the arrow 6 in doffing (see Fig. 1) the shoulder 2 will not be moved away from the catch, but, on the contrary, toward it, thus effectually preventing the spindle from 65 being lifted from the bolster or tube e .

When it is desired to remove the spindle and sleeve-whirl from the bolster and tube e the spindle will be tipped in the direction of the arrow 5, which will move the lower end of 70 the sleeve-whirl sufficiently far in the direction of the arrow 6, Fig. 1, to bring the edge of the shoulder 2 against the tube e , or far enough to afford a sufficient space between the edge of the said shoulder and the catch 3 to 75 permit the shoulder of the sleeve-whirl to rise past the said catch, as will be understood. The yielding packing aids materially in insuring efficiency of operation of the catch and shoulder of the sleeve-whirl. The catch will 80 preferably be undercut to insure its better engagement with the shoulder 2 of the sleeve-whirl, it being suitably shaped to correspond with the under side of the catch.

The bolster herein shown is represented as 85 sectional; but such a bolster is not of my invention.

I claim—

The spindle and its attached sleeve-whirl, provided with the shoulder 2, combined with 90 the bolster, the elastic packing external to the said bolster, and the bolster-supporting tube e , provided with the catch 3, to co-operate with the shoulder 2 of the sleeve-whirl, as described, and for the purposes set forth.

In testimony whereof I have signed my name to this specification in the presence of two subscribing witnesses.

RIMMON C. FAY.
